UNITED STATES PATENT OFFICE.

CHARLES F. PYM, OF DETROIT, MICHIGAN, ASSIGNOR, BY MESNE ASSIGNMENTS, TO UNITED SHOE MACHINERY CORPORATION, OF PATERSON, NEW JERSEY, A CORPORATION OF NEW JERSEY.

LASTING-MACHINE.

1,288,440.

Specification of Letters Patent. Patented Dec. 17, 1918.

Application filed September 18, 1913. Serial No. 790,003.

To all whom it may concern:

Be it known that I, CHARLES F. PYM, a subject of the King of Great Britain, residing at Detroit, county of Wayne, State of Michigan, have invented an Improvement in Lasting-Machines, of which the following description, in connection with the accompanying drawings, is a specification, like letters on the drawings representing like parts.

This invention relates to lasting machines for use in the manufacture of boots and shoes, and has for its object to provide a simple machine, operating on a novel principle, and capable of great speed and high efficiency.

Heretofore lasting machines have been either of the "hand-method" type, employing pincers which were reciprocated toward and from the shoe to embrace, grip and pull the upper leather about the wood of the last; or of the "wiper" type, which employed a wiping plate or plates to smooth, strain, or wipe the upper into place over the bottom of the last. The pincer machines are most efficient in operating on the sides of the shoe, whereas the wiper type are found to be more advantageous in lasting the heel seat and toe portions of the shoe. My present invention enables me to provide a machine utilizing the advantageous features of both the hand method and the wiper type, producing a "wiping grip" on the upper and furthermore securing the advantages of a gripping pull on the upper around the forepart, together with a wiping action on the toe and heel part. Moreover, I secure these twofold advantages by means of the same instrumentalities, *i. e.* combined positively gripping and wiping means. This feature is a distinct novelty in the art of lasting boots and shoes, and I therefore wish to claim the same broadly.

The hand method type of machine using grippers is somewhat limited as to speed of operation because of the complex movements of the pincers which are first moved downwardly toward the shoe to be in position about the upper leather, then are closed, then are moved upwardly to exert a vertical pulling tension, and are then moved or swung inwardly to overdraw the upper into position to permit the driving of the lasting tack. The machine of my present invention is organized to permit a much more rapid

operation while securing a satisfactorily positive grip and pull on the upper. The multiplicity of movements of the various gripping devices above outlined is eliminated and I employ a single engaging, gripping and stretching or pulling action on the leather. This feature is of particular importance and enables me to operate my improved type of lasting machine at high speed, and with simple mechanism. Lasting machines of the "wiper" type, such as shown in my prior Patents Nos. 880,401, 881,441 and 882,018, or of the socalled "bed lasting" type, depend upon a wiping action to last the upper, and if grippers are also employed, as in my Patent 865,936, they also were moved vertically and were independent of the wiping action and are relatively slow in their gripping action. My present invention utilizes gripping jaws which exert a horizontal, as distinguished from a vertical or upward, pulling action on the leather, gripping the projecting edge portions of the upper leather directly at the edge of the last and on a minimum of projecting material. My invention thus contemplates lasting by grippers, in a power actuated machine capable of running at high speed, utilizing a wiping grip and combining therewith a wiping action like the machines of my prior patents above mentioned, whereby I am enabled simultaneously to both pull and wipe the upper leather over the edge portion of the last and preferably by the same instrumentalities, *i. e.* by combined gripping and wiping means.

The machine of my present invention in its novel operation of securing a substantially horizontal wiping-grip on the upper leather, will operate with equal accuracy, whether the upper leather is cut "full" or "scant", gripping the edge portion of the upper, whether it projects but little or considerably above the edge of the last, whereas formerly great difficulty was experienced in lasting machines employing grippers because often sufficient upper material would not project above the last to give the grippers a hold. This was especially true in case the upper was cut "scant" and consequently the machine grippers failed to act, and uppers of this sort had to be lasted by hand. If uppers are cut with fullness to enable the grippers to secure the proper hold the extra material has subsequently to be trimmed off,

necessitating a considerable waste of upper leather, whereas in my present type of lasting machine, such a waste of material is obviated. This advantage results from my 5 invention largely because it utilizes a substantially horizontal pull or wiping grip on the edge portion of the leather, as distinguished from a substantially vertical pull and grippers to exert such a vertical pull. 10 This horizontal wiping grip, furthermore, is effected by instrumentalities which produce the gripping pull with an upwardly straining action on the leather, thus constantly tending to tighten the leather against the 15 wood of the last and counteracting any slipping of the leather in the grippers. The grippers, or one of the gripper members, are arranged to swing in an arc with the lowest point of said arc at the edge of the last and 20 will therefore give an increasing tightening or upwardly straining pull upon the leather gripped, and offset any slipping of the leather through the grippers during the continued swing of the gripper or grippers in 25 said arc.

Another feature of importance in my present invention is that I provide mechanism capable of rapid use in lasting the side and toe portions of the shoe by positively 30 gripping and pulling the leather, and which with equal facility, will last and form the heel seat of the shoe, with the additional advantages incident to a wiping action at the heel seat, enabling the operator to go 35 entirely around the shoe bottom in the lasting process and complete this operation both on the forepart and around the heel with a single machine. Thus an operator with a single handling of the shoe, while it is in 40 position, can complete the lasting of the forepart and formation of the heel seat, by means of instrumentalities peculiarly advantageous for each operation. Preferably I arrange the grippers which constitute the 45 combined pulling and wiping means for lasting the shoe, to be reciprocated in a definite vertical plane extending from front to rear of the machine and the operator may hold the shoe with the adjacent portions of 50 its edge either at right angles to this plane of reciprocation or at any desired angle thereto, as in going around the toe, for example, to facilitate the pulling of the upper and plaiting of the upper material about 55 the curved contour of the toe. As the pulling and wiping grippers move at high speed, approximately at the rate of 2000 movements per minute, my lasting machine produces a progressively continuous pulling action 60 on the upper leather, and thus eliminates all chance for wrinkles or unevennesses in the leather as it is wiped, pulled and stretched over the edge of the last, either along the sides or at the toe and heel of the 65 shoe. My present machine is capable of a

higher speed of operation than any power gripper-lasting mechanism, and this high speed, combined with the positive gripping and wiping action, each gripping action overlapping the preceding, effects substantially continuous pulling of the leather, which is a distinct novelty in the lasting art, and which I wish to claim broadly. 70

In the preferred embodiment of my invention as herein shown, I employ a positively actuated, horizontally reciprocating wiper member which coöperates with a movable gripping device, yieldingly held toward the wiper member and together constituting the grippers which grip and pull the leather during the forward or wiping movement of the wiper member. In a modified form I show the wiping member as coöperating with and actuated simultaneously with the members which are structurally separate 80 from the wiper, and in each form the lasting action is accompanied by a simultaneous wiping and pulling of the leather in a substantially horizontal line as distinguished from prior lasting devices which pulled the 85 leather in a vertical direction. The coöperating gripping devices, whether a single member acting with the forward end of the wiper or a pair of grippers acting in combination with the wiper, may have a pivotal 90 action, but this will simply tighten their hold upon the leather and does not pull the same vertically, while it does tend to exert a slight upward straining or swinging tension. To facilitate the use of my improved 95 lasting machine for operating entirely around the shoe including the sides, toe part and heel, I preferably arrange suitable guides, one for use around the toe or heel, and the other for the sides and 100 shank of the shoe, one of the guides being adapted to be quickly swung into or out of operative position and when in its inoperative position to expose the other guide for 105 use. 110

The terms "positive" and "positively" as used in this specification in connection with the gripping of the upper against the wiper are used to designate an actual grasping and pulling of the leather as distinguished from 115 a mere wiping action, it being understood, of course, that as the stretch is removed from the leather by the constantly repeated pulls, there will be more and more slipping of the leather between the gripping surfaces. 120

Other features of the invention, novel combinations of parts, and details of description will be hereinafter more fully pointed out and claimed.

Referring to the drawings.

Figure 1 is a side view of a preferred embodiment of the invention, wherein a type of wiping-gripper comprising a single gripping member coöperating with the wiper member is illustrated;

Fig. 2 is a side view of a modified form, wherein the wiping gripper comprises two gripper members actuated by the wiper and cooperating therewith;

5 Fig. 3 is an end view of the form illustrated in Fig. 1;

Fig. 4 is a cross sectional view on the line 4-4 of Fig. 3; and

10 Fig. 5 is a plan view of the form of wiping gripper shown in Figs. 1, 3, and 4.

In the embodiments of the invention shown in the drawings, I have used, for illustrative purposes, a lasting machine of the type shown in my prior Patent 881,441, 15 to which patent reference may be made for the details of construction, operation of the wiping and tacking mechanisms, arrangement and timing of the cams, clutch, etc. The machine may be suitably mounted 20 on a pedestal 1, and comprises a head 2 having a slideway 3 in its forward portion to contain a vertically reciprocable bar 4, carrying the tack driver operating in the nozzle 5 and actuated by a lever 6, which 25 lever is pivoted to the head 2 at 7 and is rocked by an appropriate cam connected by a single revolution, treadle-controlled clutch as in said Patent No. 881,441 to a continuously running pulley on a shaft 8 which is 30 mounted in bearings at the rear of the machine. A wiper bar 9 is pivoted at 10 to the upper end of a link 11 which has its other end pivoted at 12 to a rigid bracket 13, affixed to the head 2, said wiper being 35 arranged for endwise reciprocating and oscillating movement with and about pivot 10 in a vertical plane extending from front to rear of the machine. This motion is derived from an eccentric 14 on a shaft 15 40 adjacent the cam shaft 8 at the rear of the machine. The driving pulley is geared to shaft 15, as shown in Fig. 1, to cause the latter to run at a relatively high speed, both shafts being rotated from any suitable source 45 of power. The forward portion of the wiper bar 9 will, by said eccentric and link, thus be given a movement in a substantially elliptical path which, when a shoe is in position to be rubbed, will comprise a forward stroke 50 in a nearly horizontal plane in rubbing contact with the upper, a slight lift and a return stroke out of contact with the shoe, as fully explained in my said Patents 880,401 and 881,441. The forward or operating portion 55 of the wiper 9 comprises a forked wiping plate 16, Fig. 5, pivoted at 17 in a suitable recess in the bar 9, and is normally held downwardly by a spring 18. The forward portion of the wiper plate 16 is forked 60 to straddle the tack nozzle 5, so that a tack may be driven therethrough in response to movement of treadle rod 60, Fig. 1, when the wiper is at the extreme forward limit of its wiping action. I may also employ a 65 presser 19 pivoted at 20 to the head 2, and

actuated by a link 21, which presser is also forked at 22 to straddle the tack nozzle 5, and fits within the forked plate 16 of the wiper bar, as also shown in my said patent, although the use of such presser is entirely optional.

To coöperate with the wiper plate 16 and to constitute a wiping gripper, and therefore to provide means to positively grip, hold and pull the leather of the shoe during 75 the wiping action, I provide a jaw 23 pivoted or otherwise movably held to any suitable part of the head 2, as on a pin 24, see Figs. 1 and 3, supported between flanges 25 and 26 formed on the forward portion of 80 the slideway 3. The lower end 30 of the jaw 23 is preferably made so as to coöperate with the end of either of the forks of the plate 16, to facilitate lasting on either side of the shoe, i. e. from left to right of the 85 machine, or from right to left, and in order to readily adjust the jaw 23 to coöperate with either of said forks of the plate 16, the flanges 25 and 26 are spaced apart and an intermediate guide 27 (see Fig. 3) is 90 formed, so that the bar 23 may be held in position to coöperate with either fork of the wiper 16. When it is desired to last a shoe by moving it from right to left, viewing Fig. 3, the jaw 23 will be fitted between 95 the guide 27 and the outer flange 26 by simply sliding it along the rod 24 to the position shown in Fig. 3, then the end 30 of the jaw 23 and the right hand fork of the wiper 16 will coöperate to last a portion 100 of the shoe upper prior to the driving of the tack. In order to arrange the jaw 23 to coöperate with the other fork of the wiping plate 16 to last a shoe being drawn from left to right viewing Fig. 3, 105 it is only necessary to lift the jaw 23 and slide it on the rod 24 to position between the guide 27 and left hand flange 25. A U-shaped spring 28 is fitted about the end 110 portions of the rod 24 with its inner ends bearing upon stops 29 and its U-shaped portion across the bar 23, so that the same will be held yieldingly with its lower end 30 in position to coöperate with either fork of the plate 16 as already explained. An adjustable stop 31 is threaded through the bar 23 so as to limit the closing movement of the jaw 23 relatively to the wiper 16 as the latter is retracted and thus to permit a 115 feeding of the shoe by the operator.

In order to provide a suitable work rest for the side of the shoe being operated upon, the bracket 13 is fitted with a slideway 32 in which the shank 33 of a carrier 34 is adjustably secured, said carrier having provision to support a rotary work rest 35, similar to that illustrated in my Patent 881,441, and a straight edged work rest 36. The rotary work rest 35 is found preferable 125 for use in lasting around the heel and toe 130

part, whereas the straight edged work rest 36 may be more advantageously employed while lasting along the sides and shank of the shoe. These two work rests are preferably arranged to be interchangeable, any mechanism to accomplish this result being suitable. As herein shown, the straight edged work rest 36 is secured to the carrier 34 by bolts 37 and the rotary work rest 35 is held by an arm 38 fitting in a socket 39 in the carrier 34 and adapted to be swung into or out of position, when swung into position preferably projecting slightly forward of the rest 36 as clearly shown in Figs. 1 and 2.

15 The operation of my improved machine and the production of a wiping grip will, it is believed, be readily understood. During the operation of the mechanism, the wiper bar 9 as it is reciprocated to and fro in its 20 wiping action, will cause the forks of the plate 16 to engage the leather of the upper with their ends 40, one of which during its continued forwardly wiping action will press the leather so engaged against the co-operating end portion 30 of the jaw 23, thus effecting a gripping action, which grip is initiated by the single forward wiping movement of the wiper. When the leather is thus gripped, the continued wiping action 25 of the forks 40 will not only wipe, but pull the leather of the shoe firmly and positively to the completion of their forward wiping action. If it is desired to secure a more nearly positive grip upon the upper, either or both 30 gripping surfaces of the jaw 30 and the forks 40 may be corrugated. Any suitable controlling means may be utilized for causing the tacking mechanism to drive a tack automatically after as many wiping gripping actions 35 of the wiper mechanism as is desirable or, as shown in my said Patent 881,441, at the will of the operator. As the wiping plate 16 is given a slight orbital action during its horizontal reciprocations, due to the link 11 and 40 eccentric 14, the gripping portion 30 of the jaw 23 will secure its gripping hold slightly under the co-operating edge 40 of the wiper 16 and a close grip is thus obtained directly 45 at the edge of the last, so that the shoe upper 50 may be cut scant and still will be gripped and pulled by my wiping gripper as above explained. This wiping grip not only pulls and smooths the leather, but does so in a substantially single action and in a single line 55 of movement, *i. e.* in a substantially horizontal line; the leather engaging, leather gripping and leather pulling actions, all being substantially components of the forward or wiping movement of the mechanism, 60 thus produce a most effective wiping and gripping or combined wiper-gripping action. Moreover, the wiping grip may be only enough to apply a relatively light pull to the upper, well within what the particular 65 upper stock can safely bear, and yet the con-

stant rapid repetition of the light pull produces a greater lasting effect than could possibly be secured by a single powerful pull without injuring the upper.

I have illustrated in Fig. 2 a modified 70 form of wiping-gripper, wherein a similar wiper bar 41 is provided to effect the wiping and pressing of the upper leather, together with independent co-operating gripper jaws 42 and 43, which gripper jaws effect 75 the gripping of the leather and are given a pulling action in combination with the independent lasting action of the wiper, 41. In this construction, the gripping and wiping are effected by different mechanisms, but 80 the gripping and wiping are component portions of a wiping gripping, lasting movement, effected substantially simultaneously. The jaws 42 and 43 may be suitably actuated by the movement of the wiper bar 41 and 85 I have so shown them. The jaws 42 and 43 are illustrated in Fig. 2 as pivoted at 44, the jaw 42 having an extension 45, with its outer end pivotally connected at 46 to a link 47, which link has its other end pivotally attached at 48 to the wiper bar 41. The jaw 43 is formed with an extension 49 pivoted at 50 to a bar 51, which bar in turn is pivoted at 52 to the head 2. A spring 53 is arranged to bear on the bar 51 and normally hold the 90 same downwardly with its rear end against a stop pin 54. During the operation of the wiper bar 41 as the same is given its horizontal reciprocation, the jaws 42 and 43 will be first closed to grip the upper leather and 100 then actuated to pull it as the wiper 41 is moved forwardly and said jaws will be opened during the retractive movement of the wiper bar after contact of the rear end of the bar 51 with the stop pin 54 in a manner similar to that explained in connection with the single jaw 23 co-operating with the wiper bar itself and with a similar result.

It will thus be seen that I have provided 110 a lasting machine operating on a novel principle and capable of running at exceptionally high speed, causing the upper pulling movements to follow each other in such rapid succession that the upper is unable to recover itself between pulls and is by successive increments pulled into lasted position. It is broadly new to provide lasting means which grip the upper and operate at sufficiently high speed to effect a substantially continuous pulling action on the upper; such continuous pulling being also carried on progressively around the entire shoe bottom including the heel, being preferably effected at substantially a right angle to the portion of the edge of the last, which for 115 the time being, is presented to the lasting devices, the said angle being variable by the operator at will. While such substantially continuous lasting is a distinct and separate feature, the means for effecting such pro- 120

125 130

gressively continuous lasting is preferably my novel form of wiper-gripper which itself constitutes a novel lasting means. The combination of a positive gripping strain on the upper with a wiping action has never before been accomplished, so far as I am aware, and this feature, while capable of operation at sufficiently high speed to effect a substantially continuous pulling, may of course be independently employed in any machine, particularly in a machine of the bed lasting type. I have coined the phrase "wiping-gripper" to define my combined gripping and wiping device. This phrase also designates the means employing the novel principle embodied in my machine, whereby the upper is lasted by a substantially single movement; *i. e.*, by a lasting device positively engaging the leather, wiping the leather over the last edge, gripping the leather, and then pulling and lasting it by positively straining and stretching the leather, all in one forward motion. Preferably this single movement whereby the several functions above noted are accomplished, is in a substantially straight line, although of course it may be in a curved line, the important feature being that these several motions are performed as a single movement and almost instantaneously. This is of special importance in distinguishing from the old style lasting machines using grippers to which were imparted three, four, or more distinct successive movements, *viz.*, moving toward the leather, closing on the leather, pulling upwardly, and then pulling inwardly, as well as distinguishing from the prior bed-lasting type of machine using wipers which simply wiped or slid across the leather without positively gripping and stretching.

Having described my invention, what I claim as new and desire to secure by Letters Patent is:

- 45 1. A lasting machine, comprising leather wiping means and leather gripping means, said wiping means being actuated to exert a wiping lasting action on the leather prior to the lasting action of the gripping means.
- 50 2. A lasting machine, comprising leather wiping means and leather gripping means having a lasting action, said wiping means being actuated to exert a wiping lasting action on the leather prior to the lasting action of the gripping means and to continue the lasting action of said wiping means during the lasting action of the gripping means.
- 55 3. A lasting machine, comprising leather wiping means and leather gripping means, said wiping means being actuated to exert a wiping lasting action on the leather prior to the lasting action of the gripping means, the continuing lasting action of the wiping means actuating the gripping means.
- 60 4. A lasting machine, comprising leather

wiping and gripping mechanism, tack driving mechanism, automatic means to operate said wiping and gripping mechanisms, and means operable at will to actuate the tack driving mechanism.

5. A lasting machine, having in combination automatic gripper lasting means and automatic wiper lasting means, together with mechanism to actuate first said wiper means and then said gripper means at the same portion of a shoe upper and as a continuous lasting action on said upper.

6. A lasting machine, having in combination means to exert a gripping lasting pull in a substantially horizontal plane, but with an upward straining action on the leather, and means to exert a wiping lasting action, as a single operation.

7. A lasting machine, having in combination gripper lasting means, wiper lasting means, and tack driving mechanism, said lasting means being successively operated at high speed, together with means to actuate the tack driving mechanism for a single movement at any time after the completion of a combined wiping and gripping lasting action, during the continuous operation of said wiper and gripper lasting means.

8. A lasting machine, having in combination gripper lasting means and wiper lasting means, mechanism to operate said lasting means successively, conjointly, and repeatedly on the same portion of the work, together with tack driving mechanism operable at will.

9. A lasting machine, having in combination, means to exert a positive pulling tension, continuously running means to exert a wiping action on the same portion of the upper, and tack driving mechanism constructed and arranged to be operated at the will of the workman to insert a tack.

10. A lasting machine, having in combination, tack driving mechanism operable at will, means to exert a plurality of gripping lasting actions on the upper in advance of the action of the tack driving mechanism, and means to exert a wiping action on the upper during each gripping action.

11. A lasting machine, having in combination, tack driving mechanism operable at will, means to exert a gripping lasting action on the upper in advance of the tack driving operation, and means to exert a wiping action on the upper simultaneously.

12. A lasting machine, comprising rapidly moving gripping means arranged to act on the upper in a line substantially parallel with the last bottom, in combination with means to drive a lasting tack after a plurality of lasting actions of said gripping means.

13. A lasting machine, comprising gripping means arranged to exert their pulling action on the upper by a continued move-

- ment on the line of movement closing said grippers, in combination with means to drive a lasting tack after a plurality of lasting actions of said gripping means.
- 5 14. A lasting machine, comprising means to wipe, grip, and pull an upper to last a shoe as steps in the order recited of a single movement of the lasting devices.
15. A lasting machine, comprising means to wipe, grip, and pull an upper, to last a shoe as steps in the order recited in the forward gripper closing movement of a lasting device.
16. A lasting machine, having means to engage, to wipe, to grip, and to pull the upper leather over the edge of a last by successive operations in the order recited, and operating mechanism for giving said means a substantially uninterrupted advance as one continuous operation, and approximately in a straight line.
17. A lasting machine having, in combination, means constructed and arranged to be actuated to engage, to wipe, to grip and to pull the upper leather of a shoe over the edge of its last, a rest against which the shoe is held for the operation of said means, and mechanism organized to actuate said means to effect said movements successively in the order recited as one continuous operation and in a line approximately parallel to the last bottom.
18. In a lasting machine, tack driving mechanism, in combination with means to exert a substantially continuous lasting action on the upper, comprising means to wipe the upper over the edge of the last, and an upper gripping member coöperating with the wiping mechanism during the wiping action.
19. In a lasting machine, tack driving mechanism, in combination with means to exert a substantially continuous lasting action on the upper, comprising means to wipe the upper over the edge of the last, and means to grip the upper during the wiping action.
20. In a lasting machine, tack driving mechanism, in combination with means to exert a substantially continuous lasting action on the upper, comprising means to wipe the upper over the edge of the last, and yieldingly held means coöperating with the wiper to grip and pull the upper during the wiping action and operated by the wiping mechanism.
21. In a lasting machine, tack driving mechanism, in combination with a forked wiping member and a gripping member co-operating with one fork to grip the upper during the wiping action.
22. In a lasting machine, tack driving mechanism, in combination with a forked wiping member and a gripping member, adapted to coöperate with one fork to grip the upper during the wiping action, said gripping being initiated by the forward movement of the wiping member.
23. In a lasting machine, tack driving mechanism, in combination with a forked wiping member having means coöperating with either fork at will to grip the upper between said parts during the wiping action.
24. In a lasting machine, tack driving mechanism, in combination with a forked wiping member, and a single coöperating leather gripping member adjustable to coöperate with either prong of said fork at will.
25. In a lasting machine, tack driving mechanism, in combination with a forked wiping member, a single coöperating leather gripping member adjustable to coöperate with either prong of said fork at will, and means to hold said coöperating member in operative position with either fork.
26. In a lasting machine, tack driving mechanism operable at will, in combination with a horizontally reciprocable wiper member and pivotally mounted gripper means coöperating with said wiper member and actuated thereby to last the upper.
27. In a machine for progressively lasting shoes, the combination with a wiper and means for reciprocating the wiper over a shoe bottom, of a gripper member extending into the path of the wiper and movable thereby, said member being arranged for the upper to be clamped against it and pulled by the advancing wiper.
28. In a machine for progressively lasting shoes, the combination with a wiper and means for reciprocating the wiper over a shoe bottom, of a gripper member mounted in the path of the wiper, means to press said member yieldingly toward the wiper and cause it to engage the inner side of the upper, and means to limit the movement of said gripper member toward the wiper whereby separation is produced as the wiper approaches the limit of its rearward reciprocation.
29. In a machine for progressively lasting shoes, the combination with a wiper and means for reciprocating the wiper over a shoe bottom continuously, of means operating automatically to hold the upper against the end of the wiper as the wiper advances, whereby to increase the effect of the wiper in drawing the upper over the shoe bottom.
30. In a machine for progressively lasting shoes, the combination with a wiper and means for reciprocating the wiper over a shoe bottom, of yieldingly mounted means formed to extend downwardly and rearwardly to reach under the margin of the upper material and having a face against which the end face of the wiper grips the upper to draw it as the wiper advances.

31. In a machine for working an upper over a last, a gripper mechanism comprising a jaw having laterally disposed gripping faces and a jaw that is adjustable laterally 5 to different positions to adapt it to coöperate with either of the laterally disposed gripping faces of the other jaw.

32. In a machine for working an upper over a last, a tack driving mechanism, a 10 gripper jaw occupying a laterally symmetrical relation to the tack driving mechanism and having a gripping face at each side of said mechanism, and a coöperating jaw adjustable to coöperate with the first jaw at 15 either lateral side of the tack driving mechanism.

33. In a machine for effecting progressive lasting, a gripper constructed and arranged to be actuated to approach and pull an upper 20 by a continuous movement in one general direction, and operating mechanism constructed and arranged to cause a succession of such actuations with such rapidity that the upper is unable to recover between 25 pulls and is worked into lasted position by a succession of stretching increments.

34. In a machine for effecting progressive lasting, the combination of suitable operating mechanism and a gripper constructed 30 and arranged to wipe each portion of the upper to be worked into lasted position by a succession of stretching increments, and means to insert upper fastening tacks at the will of the operator.

35. In a machine for effecting progressive lasting, a gripper constructed and arranged to wipe and pull the upper, and operating mechanism organized to adapt it to effect 40 repeated operations of said gripper means in quick succession upon the same portion of the work, combined with power tacking mechanism arranged to allow a plurality of operations of the said gripper means between successive tack driving operations.

45. 36. In a machine for effecting progressive lasting, the combination of a wiping gripper comprising one member arranged to have a wiping movement over the outer face of the marginal portion of an upper and a 50 second member against which the first member grips the margin of the upper and between which and the first member the upper is pulled, and mechanism to cause said wiping gripper to repeat its operation rapidly without interruption between repetitions.

37. A lasting machine comprising a combined wiping and gripping mechanism to work a shoe upper over the edge of a last, 60 and means to cause said mechanism to repeat its operation uninterruptedly at high speed, in combination with means to insert fastenings in the formed upper at the will of the operator.

65. 38. A lasting machine comprising gripp-

ers, automatic mechanism to actuate said grippers to engage the upper and to impart to a gripper member a wiping action, said machine being organized to cause said grippers to repeat their operation uninterruptedly at high speed while a shoe is so presented and advanced as to cause the operation of the grippers to be repeated on the same or closely adjacent parts as the shoe is progressively lasted.

39. A lasting machine comprising leather grippers, automatic mechanism to actuate said grippers to engage the leather and to impart to a gripper member a wiping action, said machine being organized to cause said grippers to repeat their operation uninterruptedly at high speed while a shoe is so presented and advanced as to cause the operation of the grippers to be repeated on the same or closely adjacent parts as the shoe is progressively lasted, and tack driving mechanism arranged for operation at will to fasten the upper.

40. A lasting machine having, in combination, tack driving mechanism, means including a gripper constructed and arranged to wipe an upper, and operating mechanism organized to effect repeated operations of the gripper between two operations of the tack driving mechanism.

41. A lasting machine having, in combination, tack driving mechanism arranged to insert a tack at the will of the operator and wiping-gripper mechanism organized to make a plurality of complete cycles between 100 tack inserting operations.

42. A lasting machine having, in combination, tack driving mechanism arranged to insert a tack at the will of the operator and wiping-gripper mechanism arranged to effect a combined pulling and wiping action on the upper leather and organized to repeat its operation uninterruptedly at high speed unaffected by the operation of the tack driving mechanism.

43. In a lasting machine, tack driving mechanism, in combination with a wiping gripper which is arranged to grip and pull the upper with a wiping action and to effect an upward strain on the upper.

44. A lasting machine having, in combination, tack driving mechanism, wiping lasting means arranged to operate at both lateral sides of the tacking point and gripping lasting means arranged to operate at one lateral side of the tacking point.

45. A lasting machine having, in combination, tack driving mechanism, wiping lasting means comprising a wiper forked to embrace the tack driving mechanism, and a gripper member arranged to coöperate with a fork of the wiper on one lateral side of the tacking mechanism.

46. A machine for effecting progressive lasting having, in combination, tack driving

mechanism, wiping lasting means comprising a wiper forked to embrace the tack driving mechanism, and a gripper member arranged to coöperate with a fork of the wiper 5 on one lateral side of the tacking mechanism, said gripper member being adjustable to coöperate with that fork of the wiper which is on the leading side of the tacking mechanism considering the direction in which the lasting 10 operation is progressing.

47. A machine for effecting progressive lasting having, in combination, tack driving mechanism and gripper mechanism comprising a gripper adjustable to occupy a 15 working position at either lateral side of the tack driving mechanism alternatively.

48. A lasting machine adapted to operate upon the side, toe and heel portions of boots and shoes, having, in combination, tack driving mechanism; means to work the upper over the edge of the last entirely around said side, toe and heel portions; a shank guide for use in lasting the side of the shoe; and a toe and heel guide mounted to cover the 20 shank guide while in operative position and to swing laterally to an inoperative position 25 and uncover the shank guide.

49. In a machine for progressively lasting shoes, the combination with fastener inserting mechanism and a tool to form the margin of the upper over against the margin of the last bottom into position to be fastened by said mechanism, of a member arranged to coöperate with the tool to clamp 30 the margin of the upper, and power driven means for relatively moving the shoe and the tool and said member to effect clamping of the upper and drawing and forming of it over against the last bottom.

50. In a machine for progressively lasting shoes, the combination with fastener inserting mechanism and a tool to form the margin of the upper over against the margin of the last bottom into position to be fastened by said mechanism, of a member arranged to coöperate with the tool to clamp 35 the margin of the upper, and power driven means for relatively moving the several parts of the machine and the last to effect 40 clamping of the upper between the forming tool and said member, pulling of the clamped upper over the margin of the last bottom, and fastening of the upper.

51. In a machine for progressively lasting 45 shoes, the combination with fastener inserting mechanism and a tool to form the margin of the upper over the margin of the last bottom into position to be fastened by said mechanism, of a member arranged with relation 50 to the tool to effect gripping of the upper against the tool during relative movement of the tool and the shoe and to yield to effect pulling of the gripped upper during continued relative movement of the tool and 55 shoe for carrying the upper over the shoe

bottom, and operating means organized to effect said relative movements and to cause insertion of fastenings for securing the pulled upper.

52. In a machine of the class described, 70 mechanism to work a shoe upper over the edge of the sole or innersole, including upper gripping and upper wiping means to work the upper over the last by repeated operations toward the point at which a tack is 75 to be driven, in combination with means under control of the operator to drive a lasting tack at the completion of a forward lasting operation of the upper overworking devices. 80

53. In a lasting machine, means constructed and arranged to engage the upper at the edge of the last and to wipe the upper inwardly when the shoe is held in proper lasting position with relation to the machine, and means for rapidly reciprocating said wiper with a speed causing said wiping actions to follow each other in such quick succession that the upper is prevented from recovering itself between the wiping actions 90 and is gradually forced into fully lasted position by a succession of stretching increments, combined with means between which and the wiper the upper is gripped and which is thereafter moved with the wiper 95 to effect a pulling of the upper supplemental to the wiping. 100

54. In a lasting machine, means constructed and arranged to engage the upper at the edge of the last and to wipe the upper inwardly when the shoe is held in proper lasting position with relation to the machine, and means for rapidly reciprocating said wiper with a speed causing said wiping actions to follow each other in such quick succession that the upper is prevented from recovering itself between the wiping actions and is gradually forced into fully lasted position by a succession of stretching increments, said mechanism including means 110 to maintain the wiper in sliding contact with the upper from the edge of the shoe bottom inwardly and out of contact with the upper during its backward reciprocatory stroke combined with means between which and the wiper the upper is gripped and which is thereafter moved with the wiper to effect a pulling of the upper supplemental to the wiping. 115

55. In a step by step lasting machine, the 120 combination with a reciprocating wiper of a member arranged in the path of the wiper and movable by the wiper in the direction of its wiping movement and between which member and the end of the wiper the upper 125 is gripped to effect a pull on the stock in addition to and during the wiping of the upper over the shoe bottom.

56. In a step by step lasting machine, the 130 combination with a wiper having an orbital

path of movement carrying it inward over the shoe bottom in wiping contact with the upper and thence upwardly and backwardly out of dragging engagement with the overwiped stock, of a resiliently mounted member located in the path of the wiper and arranged to engage the inner side of the stock while the wiper engages the outer side and coöperating therewith to pull the stock over the last while it is being wiped by the wiper.

57. In a machine of the class described, mechanism to work a shoe upper over the edge of the sole or insole and secure it, comprising means to drive a tack, means to last the upper comprising a plurality of recipro-

cating lasting wipers, and means to actuate said wipers a plurality of times before a lasting tack is driven, in combination with means to engage and hold the upper during the tack driving operation independently of 20 the wiping and retracting movements of said wipers.

In testimony whereof, I have signed my name to this specification, in the presence of two subscribing witnesses.
